UNITED STATES PATENT OFFICE.

KATHERINE F. MURRAY, OF ALBANY, NEW YORK.

DESIGN FOR A CHART FOR COLOR STUDY.

SPECIFICATION forming part of Design No. 34,592, dated May 28, 1901.

Application filed April 18, 1900. Serial No. 13,396. Term of patent 14 years.

To all whom it may concern:

Be it known that I, KATHERINE F. MURRAY, a citizen of the United States, residing at Albany, in the county of Albany and State of New York, have invented and produced a new and original Design for a Chart for Color Study, of which the following is a specification, reference being had to the accompanying drawing, forming part thereof.

The drawing is a diagram illustrating my design for a chart for color study and shows the several features and their relative arrangement in the design.

As shown in the drawing, the leading or material features of my design consist of a series of central semicircular fields A, B, and C, an outer series of equidistant circular disks D, arranged on a line of a half-circle and having each its surface divided into three fields, as a, b, and c, (indicated by dotted lines d,) an intermediate series of equal squares E, in pairs and also on a line of a half-circle

and divided each into fields e, e', and e'', which are separated at lines which are indicated by dotted lines e³, a series of triangular-formed fields F F', a series of radial bars G G, each connecting a disk D to the central disks A, B, and C, and a series of bars g g in pairs and branching from each radial bar G and connecting the squares F, respectively, to said bars.

Having described my invention, what I claim, and desire to secure by Letters Patent, is—

The design for a chart for color study, as herein shown and described.

In testimony whereof I have signed my name to this specification in the presence of two subscribing witnesses.

KATHERINE F. MURRAY.
